UNITED STATES PATENT OFFICE

JOSEPH D. ZUBIA AND MANUEL S. GUTIERREZ, OF LOS ANGELES, CALIFORNIA

DETACHABLE HEEL

Application filed April 21, 1930. Serial No. 446,087.

Our invention relates to boots, shoes and the like, and it has for a purpose the provision of a simple, durable and effective means for fixedly securing a heel to a shoe in such manner as to permit the ready detaching of the heel should it become damaged or unduly worn and the substitution of a new heel. Our invention also permits heels of various heights, shapes, and color to be used on one and the same shoe so that the shoe may be used as a dress or walking shoe.

It is also a purpose of our invention to provide a detachable shoe heel which is characterized by the latching means for securing the heel to the shoe being carried by the shoe and not by the heel, with the advantage of effecting a more secure support for the heel, and attaching the heel with such a degree of security as to prevent relative movement of the shoe and heel.

We will describe only one form of detachable shoe heel embodying our invention, and will then point out the novel features thereof in claims.

In the accompanying drawings:

Fig. 1 is a view showing in vertical longitudinal section one form of shoe having applied thereto one form of detachable heel embodying our invention.

Fig. 2 is a view similar to Fig. 1 showing the released position of the parts for holding the heel on the shoe incident to removal of the heel.

Fig. 3 is a vertical transverse sectional view taken on the line 3—3 of Fig. 1.

Fig. 4 is a detail perspective view of the heel detached from the shoe.

Fig. 5 is a detail perspective view of that part of the device which is pivotally attached to the shoe.

In carrying out our invention, we provide a plate 15 of metal or other suitable material including a relatively narrow portion 15^a which extends forwardly from a wide portion 15^b, the narrow portion adapted to be secured to the under-side of the instep of a shoe by means of screws or other suitable fastening members, and the wide portion adapted to be secured to the upper side of a head H. This head at the upper side is re-

cessed to receive the wide portion 15^b, and its lower side is convexed and provided centrally with a tongue T. This tongue extends longitudinally of the head H and, in cross section, is of substantially dovetail form in 55 order to coat with the groove formed in the shoe heel for mounting the heel on the shoe.

As shown in Figs. 1 and 2, the tongue is provided with a pocket 16 opening to one end of the tongue, and in which is received a 60 plunger 17 urged outwardly by a coil spring 18. At its upper side the plunger is provided with an opening 19 and at its lower side with a slot 20, this opening and slot receiving an upwardly extending arm 21 of a latch 22 65 which is pivoted in the tongue by means of a pin 23 and so as to move in the slot 24 of the tongue.

From the foregoing construction it will be clear that under the action of the spring 18, 70 the plunger 17 is urged outwardly with respect to the tongue, and in this position of the plunger the latch 22 occupies a projected position with respect to the slot 24. By pushing the plunger inwardly and against 75 the tension of the spring 18, the plunger actuates the arm 21 to swing the latch into retracted position within the slot 24. This retracted position of the latch constitutes its 80 released position in respect to the heel which it is designed in part to secure to the shoe.

As best illustrated in Fig. 4, the heel embodied in our invention and designated at L may be a heel of the Spanish type as used for dress, or a lower heel as used for walking, the 85 particular type of heel being immaterial, as it will be understood that our invention is adaptable to heels of any form, and of several forms for any one shoe to permit the shoe to be used as a walking shoe or as a dress shoe. The heel L is characterized by having an upper surface 25 of concave form to conform to the contour of the convex surface of the underside of the head H so that when the heel is applied as shown in Figs. 1 and 3 it 90 will accurately conform to the contour of the head. By reason of the contour of the head and heel, the heel is braced against wobbling movement on the head, but in addition, the heel is provided with a groove 26 having the 100

same cross sectional contour as that of the tongue T so as to receive the tongue. In the bottom of the groove 26 is a keeper member 27 for the latch 22, the latch engaging this keeper when in projected position, as shown in Fig. 1, in order to prevent withdrawal of the tongue from the groove.

In practice, the heel is applied to the shoe by presenting the concave side of the heel to the convex side of the head H and so that the groove 26 is aligned at its open end with the adjacent end of the tongue T. By advancing the heel from this position the tongue is moved into the groove, and when pushed home therein the latch 22 engages the keeper 27 and thus secures the tongue against displacement from the groove. The heel therefore is now locked to the shoe.

To remove the heel from the shoe it is only necessary to push the plunger 17 inwardly thereby retracting the latch 22 free of the keeper 27 when the tongue T can be removed from the groove 26, and the heel thus detached from the shoe.

Although we have herein shown and described only one form of detachable shoe heel embodying our invention, it is to be understood that various changes and modifications may be made therein without departing from the spirit of the invention and the spirit and scope of the appended claims.

We claim:

1. In combination, a shoe, a head secured to the shoe, a tongue on the head, a heel having a groove therein for receiving the tongue, a keeper on the heel within the groove, a latch on the tongue yieldably urged to a projected position for engaging the keeper to secure the tongue against removal from the groove, and a plunger movable in the tongue to retract the latch out of engagement with the keeper.

2. In combination, a shoe, a head secured to the shoe and having a convex surface, a tongue formed integral with the head and projecting from said surface, a plunger movable in the tongue and yieldably urged to one extreme position, the heel having a concave surface contacting with the convex surface of said head and a groove receiving said tongue, a keeper in the groove of the heel, and a latch on the tongue normally occupying a projected position to engage said keeper and movable to a retracted position by actuation of said plunger to disengage the keeper.

3. In combination, a shoe, a head secured to the shoe, a tongue on the head having a pocket therein and a slot communicating with the pocket, a plunger movable in the pocket, a spring in the pocket for urging the plunger outwardly of the latter, a latch pivoted in said slot and having an arm engaging the plunger so that in the normal position of the plunger the latch occupies a projected po-

sition, a heel having a groove therein for receiving said tongue, and a keeper on the heel engaged by the latch for securing the tongue against displacement from the groove.

4. In combination, a shoe, a head secured to the shoe, a tongue formed integral with the head, a plunger movable in the tongue and yieldably urged to one extreme position, a heel having a groove receiving said tongue, a keeper in the groove of the heel, and a latch on the tongue normally occupying a projected position to engage said keeper and movable to a retracted position by actuation of said plunger to disengage the keeper.
